CLAIM

The ornamental design for a magnetic power bank, as shown and described.

DESCRIPTION

FIG. 1 is a front, top perspective view of a magnetic power bank, showing my new design;

FIG. 2 is a rear, bottom perspective view thereof;

FIG. 3 is a front, top perspective view of the magnetic power bank, shown in an alternate configuration;

FIG. 4 is a rear, bottom perspective view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top plan view thereof;

FIG. 10 is a bottom plan view thereof; and,

FIG. 11 is another view of the magnetic power bank, shown in an alternate configuration.

The broken lines in the figures illustrate portions of the magnetic power bank that form no part of the claimed design.
